CLOSABLE CONTAINER

Otto Kasdorf, Montevideo, Uruguay

Application September 28, 1934, Serial No. 745,995
In Germany December 30, 1933

5 Claims. (Cl. 229—4.5)

This invention relates to containers of paper material, such as paper or cardboard of the kind in which the open end is closed by folding a portion of the wall of the container along pre-formed creases.

It has already been proposed to make containers of circular or elliptical cross-section of paper or the like, preferably waterproof material, and to close them by folding the upper end. 10 It is also known to provide such cylindrical or conical bottle-like containers with a four-cornered roof-shaped closing part formed by folds through previously made creases. Such a four-cornered folding has the disadvantage that the 15 paper is subjected to considerable strains and stresses, more particularly at the corners, so that the container easily tears, more particularly at those places where the circular or elliptical cross-section merges into the four-cornered cross-section.

The container according to the invention which is made of one or more layers of paper stuck together or of cardboard or some similar material, differs from these known containers in this, that the transverse folding creases, where the container body merges into the folded closure part, form a hexagon, octagon or polygon which merges at two opposite sides into two narrow inclined surfaces which are inclined towards one another like a roof and at the other sides into surfaces which fold together like a concertina. In the folding closure formed in this manner the stresses occurring at the places where one surface merges into the other are considerably 35 smaller. Furthermore, the bottle mouth formed by the folds is narrower, which provides the advantage that smaller closing clamps can be used.

A further advantage is that those sides of the polygon which merge into the folded-in surfaces may, for preventing undesired sudden bends and the strains caused thereby be formed with folding creases which extend substantially along the curves formed where the folding surfaces merge 45 into the container wall.

The invention also relates to the provision of one or more flat surfaces of the folding closure or the container body with one or more windows which allow the contents of the container to be seen. A further feature of the invention is a 50 special constructional form of closing member to be placed on the folded part of the container.

In the accompanying drawings two constructional examples of the invention are illustrated. 55 Fig. 1 shows the cut-out blank of a cylindrical

container, the closing part of which is folded to form an octagon.

Fig. 2 shows the upper part of the container with the surfaces which are folded in a starlike manner for preparing the closure and 5

Fig. 3 shows this part folded together in concertina fashion.

Fig. 4 shows the completely folded closing part of the container with the closing member to be slipped on. 10

Figs. 5 and 6 show the completely closed container in perspective view and in vertical section.

Fig. 7 shows the cut-out blank of another constructional form of container and 15

Fig. 8 this container in perspective view.

The container is made substantially of a four-cornered sheet of paper or cardboard *a*, *b*, *c*, *d*, which is rolled up over a cylindrical mandrel or a mandrel in the shape of a truncated cone and the overlapping longitudinal edges of which are 20 stuck together. The upper end of the container blank is divided up by the pressed-in creases *i* to *q*, which are required for folding the closure part, before or after rolling, into the areas 25 *1* to *8*, which with the exception of the area *1* and the overlapping areas *5*, *5'* are subdivided by further short longitudinal creases *r* to *w*. The areas *1* and *5* have no folding creases, as they 30 form the two flat surfaces of the folding closure, which lie opposite one another like the sides of a roof. On the other hand the areas *2* to *4* and *6* to *8* are additionally provided with oblique 35 creases *x* and *y* which enable these areas to be folded in in concertina fashion.

The completely cylindrical container with a 35 bottom part *10* which is inserted and fixed by an adhesive, according to Fig. 6, is closed after filling in such a manner that the areas *2* to *4* and *6* to *8* of the closure part are folded in starlike fashion and in concertina fashion by additionally pressing 40 together the surfaces *1* and *5*. On to the narrow end *m*, *n* of the closure part, which is formed by the flat surfaces *1* and *5* and the folding surfaces lying between them, a clamp *9* made of a sheet-metal strip can be slipped after a transverse fold has been made, which provides a secure 45 and liquid-tight closure, the said clamp being suitably secured against displacement by longitudinally and transversely extending pressed-in grooves. The closure is secured in a particularly 50 simple manner by impressing an undulating groove.

The constructional example shown in Figs. 7 and 8 differs from that of Figs. 1 to 6 only in this that some of the areas, for instance the areas *2* to 55

4 and 6 to 8, are bounded at the bottom, not by straight creases but by arcuate creases, which correspond substantially to the curves formed where the folding surfaces and the container wall merge into one another. When the closure part is folded these arcuate folding creases almost entirely prevent undesired straining and stressing of the paper which might result in the container becoming torn.

10 5 In the surfaces 1 and 5 or additionally in the body part of the container transparent windows 11 are formed or provided in a known manner, which enable the contents of the container to be seen or make it possible to check whether the container has been completely filled.

15 If the container be made of ordinary paper it can be made liquid-proof after its manufacture by means of paraffin or other substances.

What I claim is:

20 1. A paper container of substantially circular cross-section comprising a body portion, a reduced closure portion adjoining the body portion and having a mouth therein, a folding crease circumscribing the container at the juncture of said portions and having at least six corners, said circumscribing crease being curved between certain adjacent ones of said corners, said closure portion having opposed flat parts disposed in convergent relation, the parts of said closure lying intermediate said flat parts being creased and folded to form two groups of oppositely disposed folds extending in convergent relation, the extremities of said folds located at the mouth being disposed and held flatwise between said flat parts.

25 30 35 2. A container as claimed in claim 1 characterized in that the curvatures of the circum-

scribing crease are determined by the intersection of the planes of said folds with said body portion.

3. A container as claimed in claim 1 characterized in that the curvatures of the circum-scribing crease are determined by the intersection of the planes of said folds with said body portion, the portions of said circumscribed crease located adjacent said flat portions being straight.

4. A paper container of substantially circular cross-section comprising a body portion, a reduced closure portion adjoining the body portion and having a mouth therein, said closure portion having opposed flat parts disposed in convergent relation and being of substantially less width than the diameter of the said body portion, the parts 15 of said closure lying intermediate said flat parts being creased and folded to form two groups of oppositely disposed folds extending in convergent relation, the extremities of said folds located at the mouth being disposed and held flatwise between said flat parts.

5. A paper container of substantially circular cross-section comprising a body portion, a reduced closure portion adjoining the body portion and having a mouth therein, said closure portion having opposed flat parts disposed in convergent relation and being of substantially less width than the diameter of the said body portion, the parts 25 of said closure lying intermediate said flat parts being creased and folded to form two groups of 30 oppositely disposed folds extending in convergent relation, the folds of the two groups at said mouth having a combined depth substantially corresponding with the total width of and substantially filling the space between said flat parts.

35 OTTO KASDORF.
